UNITED STATES PATENT OFFICE.

JOHN CLARKSON FIDDYMENT, OF BALTIMORE, MARYLAND.

PRESS.

1,049,834.

Specification of Letters Patent.

Patented Jan. 7, 1913.

Application filed December 22, 1909, Serial No. 534,545. Renewed July 27, 1911. Serial No. 640,936.

To all whom it may concern:

Be it known that I, JOHN C. FIDDYMENT, a citizen of the United States, residing at Baltimore, in the State of Maryland, have 5 invented certain new and useful Improvements in Presses, of which the following is a specification.

This invention relates particularly to that 10 type of presses designed for expressing liquids from seed and similar materials, and more especially intended for the extraction of cotton seed oil from cotton seeds.

A special object of the invention is to 15 utilize, in connection with the cylinder and expressing screw therein, certain novel improvements which insure a uniform action on the material as it passes through the press, and at the same time obviating tendencies of the mass of material to rotate 20 within the cylinder or press chamber as it is advanced toward the discharge end of the same, and consequently checking any retrograde or creeping movement of the material backward toward the feeding end of 25 the machine.

Most all kinds of material, when pressure 30 is first applied, has a tendency to flow or crowd back toward the feed end of the machine with the result of interfering with the free admission of the stock to the feed chamber of the machine, for the reason that the crowded-back material occupies the space that should be occupied by the un-treated material. In presses, of the express- 35 ing type, the effect of this retrograde or creeping back movement of the material is to prevent the machine from taking the charge that is necessary to give it the proper compression, as it is well known that the amount of material introduced at the feed 40 end of a press governs the pressure therein, and should there be less material than would fill the spaces between the flights of the screw, the pressure required for a proper expressing action would not be present.

After the material has passed from the feeding end of the press cylinder for a distance of say two feet, by way of example, it is in a more compact condition, and has not 50 that tendency to flow or creep toward the feed end, and it is therefore an object of the present invention to utilize a suitable check or baffle designed to seal or close one of the screw flights so that it shall be impos-

sible for the material, after having once 55 passed the point referred to, to move back toward the feed end, and at the same time preventing the pressure that is on the material nearer the outlet end of the press chamber, (which pressure is the heaviest) 60 from being in any way communicated to the material between the feeding-in point and the point where the check baffle or stop is located. This improvement is intended to insure the press getting the material in the 65 proper amount, and to regulate the flow of the material through the press chamber from inlet to outlet in such a manner as to provide for and maintain a uniform expressing action throughout the machine.

In carrying out the invention, the same is necessarily susceptible to a wide range of structural modification without departing from the principle or sacrificing any of the advantages of the invention, but certain 75 simple and practical embodiments of the invention are illustrated in the accompanying drawings, in which:

Figure 1 is a horizontal longitudinal sectional view of a screw press, shown equipped with suitably arranged check-baffles to prevent retrograde creeping or rotation of the material, for the purposes already explained. Fig. 2 is an elevation of a fragment of the expressing screw, showing one means of interrupting the spiral flights to utilize a movable check-baffle or stop of the character shown in Fig. 1. Fig. 3 is a detail cross sectional view of the press on the line 3—3 of Fig. 1 showing the stationary check-baffles 80 or stops that may be utilized nearer to the outlet end of the press chamber at a point where the material is under greater compression and has been more compacted. Fig. 4 is a vertical cross sectional view of the press 85 illustrating a modification of the means that may be employed for controlling oppositely arranged movable baffles. Fig. 5 is a similar view showing another form of movable baffle and means for controlling the same in 90 pairs.

Like references designate corresponding parts in the several figures of the drawings.

As indicated, the improvements are particularly designed to be associated with the feed screw type of press for expressing liquids. Hence, for illustrative purposes, there is shown in the drawings a screw press em-

bodging in its organization a perforate press cylinder 1 essentially consisting of a plurality of rings 2 arranged in side by side relation, and so spaced as to provide a continuous series of annular outlet openings or slits 3 through which the expressed liquid or oil escapes to a suitable receiver therefor. Also, the press shown includes an expressing screw 4 driven by suitable means, 10 and having a tapered drum or body portion 5 and spiral carrying flights 6, which serve to pass the material through the press chamber and also place the same under compression by reason of the tapering form of the drum or body portion 5, the larger end of 15 which is disposed at the discharge end of the press chamber or cylinder.

According to the present invention, it is proposed to locate suitable check baffles at 20 proper distances or points of location away from the feeding-in end of the press, so as to hold the material up to its compression and compacted form and to prevent retrograde creeping toward the feed end. According 25 to the embodiment suggested in Fig. 1, separate parts of diametrically opposite check baffles 7 and 8 may be employed. The said baffles 7 and 8 are shown in the form of slides working in guide openings 9 provided in the cylinder walls, and the check 30 baffles 7 are shown as located nearer the feed end of the machine than the baffles 8. The baffles 7—7 are arranged diametrically opposite each other at opposite sides of the 35 press, and likewise the baffles 8, which latter are located nearer the center of the machine, but the baffles 7 and 8 at the same side of the machine may be conveniently operated in unison by means of a rocking connecting lever 10, pivotally connected at its 40 extremities as at 11 and 12 respectively to the outer ends of the baffles 7 and 8, and pivotally mounted intermediate its ends as at 13 upon a supporting bracket or the like 45 14. The pivotal support 13 for each lever 10 may be movable and spring held, as indicated at 15, to allow yielding of the parts under abnormal pressure or strain.

The baffles 7—7 and 8—8 are alternately 50 moved into and out of annular pressure retaining channels 16 which are confined between straight holding flights 17 which form the side walls of said channel 16 and interrupt the spiral passages between the flights 55 6, while at the same time permitting communication with such spiral passages by means of short, oblique connecting passages 18, as may be plainly seen from Figs. 1 and 2 of the drawings.

60 Suitable spacers 19 may be employed to hold the baffles 7 and 8 to a sufficiently close fit within their channels 16, and short operating cam sections 20 are likewise fitted at one side of the channels 16 so as to operate 65 against the inner ends of the baffles 7 and 8

to move them outward and out of the way of the advancing material. For instance, when a cam 20 moves one of the baffles 7 outward, as shown in Fig. 1, the baffle 8 connected with said baffle 7 is moved inward to an operative checking position by the lever 10, and vice versa, thus securing alternate and automatic action of the opposite pairs of connected baffles. Also, according to the present invention, at a point nearer to the 70 outlet end of the press chamber, where the material is under greater compression and has been more compacted, inwardly projecting stationary check baffles 21 may be fitted to the inner wall of the press chamber or 75 cylinder so as to project into the straight annular pressure retaining channel 22 crossing and interrupting the spiral passages between the screw flights 6. Again, where it is desirable or preferable to utilize but a 80 single pair of diametrically opposite baffles in the form of slides 23—23, a rocking operating yoke 24 may be employed in connection therewith as shown in Fig. 4. This yoke is shown as bearing against the outer 85 end of the baffle slides 23 while the inner ends of said slides are engaged by an operating cam section 25 on the screw body. The yoke 24 is placed astride the press, and the intermediate part thereof slidably engages a 90 swinging supporting bolt 26 hung on a pivotal support 27 and carrying a holding spring 28, the tension of which is adjusted by a nut 29, said spring permitting the parts to yield under abnormal or excessive strain. 100 Also, instead of movable stops which are in the form of slides, there may be employed movable stops in the form of pivoted plates or blocks 30 as shown in Fig. 5. These plates or blocks 30 are moved outward by 105 an operating cam section 31 on the screw drum or body, while their inward movement is controlled by a connecting yoke 32 placed astride the press cylinder, pivotally supported at an intermediate point 33, and the opposite extremities of which are connected by 110 the links 34 respectively with the opposite blocks 30.

From the foregoing description it will be understood that various other forms of 115 baffles may be utilized, as well as baffles arranged in different positions and operated by different means without departing from the spirit of the invention. Also, it will be understood that the straight annular pressure retaining channels may be formed in other ways than those shown in the drawings, and in fact, other details of construction resorted to so long as the idea is preserved of having a check baffle projecting 120 from the cylinder sufficiently so as to be capable of sealing the passage between the flights to check retrograde creeping of the material, and furthermore, either the stationary or movable baffles may be arranged 130

in any most advantageous position that may be selected without departing from the principle of the invention.

I claim:

5. 1. In a screw press, the cylinder, the feed screw having a straight annular pressure retaining channel interrupting the spiral passages between the flights, and means, coöperating with said passage, to prevent retro-
10 grade creeping of the material.
2. In a screw press, the cylinder, the feed screw having an annular pressure retaining channel, and a check baffle carried by the cylinder and projecting into said channel.
- 15 3. In a screw press, the cylinder, the screw having a straight annular pressure retaining channel crossing and interrupting the spiral passages between the flights, a check baffle, and means for moving said baffle into
20 and out of said channel.
4. In a screw press, the cylinder, the screw having an annular pressure retaining channel crossing and interrupting the passages between the screw flights, a check baffle, and means for moving said baffle into said channel, and means carried by the screw for moving the baffle out of said channel.
- 25 5. In a screw press, the cylinder, the screw having an annular pressure retaining channel crossing and interrupting the spiral pas-
30 sages between the flights, and also carrying a cam element, a movably mounted check baffle carried by the cylinder and movable into and out of said channel, said baffle be-
35 ing operated in one direction by the cam element, and means for operating the baffle in the opposite direction.

6. In a screw press, the cylinder, the screw provided at spaced points from the feed end of the press with separate straight annular pressure retaining channels, pairs of dia-
40 metrically opposite slidably mounted check baffles adapted to move into and out of said channels, means for connecting and operating a pair of said baffles at the same side of the press in unison, and means carried by the screw for effecting outward movement of the baffles.

7. In a screw press, the cylinder, the feed screw having a plurality of straight annular pressure retaining channels crossing and in-
45 terrupting the spiral passages between the flights, movable check baffles adapted to move into and out of the channels nearest the feed end of the machine, and stationary 50 baffle elements carried by the cylinder and projecting into the channel farthest from the feed end of the machine.

8. In a screw press, the cylinder, the feed screw having a plurality of straight annular pressure retaining channels crossing and in-
55 terrupting the spiral passages between the flights, movable check baffles adapted to move into and out of certain of said channels, and stationary baffle elements carried 60 by the cylinder and projecting into another of said channels.

In testimony whereof I hereunto affix my signature in the presence of two witnesses.

JOHN CLARKSON FIDDYMENT.
